(57) **CLAIM**

The ornamental design of a shower curtain ring, as shown and described.

DESCRIPTION

FIG. 1 is a perspective view of a shower curtain ring showing our new design;

FIG. 2 is a top plan view of the shower curtain ring in accordance with our design;

FIG. 3 is a front elevational view of our shower curtain ring;

FIG. 4 is a left side elevational view thereof;

FIG. 5 is a right side elevational view thereof;

FIG. 6 is a bottom plan view thereof; and,

FIG. 7 is a front elevational view similar to FIG. 3, but showing the shower curtain ring in an open condition.
